DESIGN FOR AN AUTOMOTIVE VEHICLE HOOD RIDGE ORNAMENT

George Berkson, Chicago, Ill.

Application August 24, 1936, Serial No. 64,553

Term of patent 7 years

To all whom it may concern:

Be it known that I, George Berkson, a citizen of the United States of America and a resident of Chicago, in the county of Cook and State of Illinois, have invented a new, original, and ornamental Design for an Automotive Vehicle Hood Ridge Ornament, of which the following is a specification, reference being had to the accompanying drawing, forming a part thereof, and in which:

Fig. 1 is a perspective view of an automotive

vehicle hood ridge ornament showing my new design;

Fig. 2 is a top plan view of the same;

Fig. 3 is a side elevational view thereof; and

Fig. 4 is a sectional view on line 4—4 in Fig. 3 looking in the direction of the arrows.

I claim:

The ornamental design for an automotive vehicle hood ridge ornament as shown.

GEORGE BERKSON.
